Primary Examiner — Jonathan J Han

(57) CLAIM

The ornamental design for a shoe as shown and described.

DESCRIPTION

The file of this patent contains at least one drawing/photograph executed in color. Copies of this patent with color drawing(s)/photograph(s) will be provided by the Office upon request and payment of the necessary fee.

1. Shoe
2. Shoe
- 1.1 : Perspective
- 1.2 : Front
- 1.3 : Back
- 1.4 : Right
- 1.5 : Left
- 1.6 : Top
- 1.7 : Bottom
- 2.1 : Perspective
- 2.2 : Front
- 2.3 : Back
- 2.4 : Right
- 2.5 : Left
- 2.6 : Top
- 2.7 : Bottom

The characteristic features of the designs reside in the shape of the heel of each shoe as shown; the parts in red represent features that are not claimed; the reproductions of designs no. 1 and no. 2 show the left shoes, the corresponding right shoes being the mirror image of those shown in the reproductions.

1 Claim, 14 Drawing Sheets
